The diagram, labeled 'Fig. 5.' at the top, shows a cross-section of a device. A vertical frame 10 is divided into two sections by a horizontal line. The upper section contains a coiled heating element 156 with a bulb 19a and a filament 32a. The lower section contains a heating element 116 with a bulb 14a and a filament 33a. A U-shaped tube 18a connects the two sections. On the left side, a vertical pipe 31 is connected to the tube 18a. On the right side, a vertical pipe 23 is connected to the tube 18a. The pipe 23 has a bulb 25a at its top. Various numbers (31, 34, 35, 18a, 19a, 32a, 156, 14a, 33a, 116, 10, 23, 25a) are used to label the components.

INERT GAS ABSORPTION REFRIGERATOR

Gunnar Axel Grubb, Bromma, Sweden, assignor to Aktiebolaget Elektrolux, Stockholm, Sweden, a corporation of Sweden

Application October 20, 1951, Serial No. 252,313

Claims priority, application Sweden October 25, 1950

3 Claims. (Cl. 62—99)

My invention relates to absorption refrigeration systems of the inert gas type, and more particularly relates to such a refrigeration system having plural temperature evaporator structure.

It is an object of my invention to provide an improved evaporator structure in which several cooling elements operable at different temperatures may be effectively employed to cool the thermally insulated interior of a refrigerator cabinet and a freezing section disposed therein. I accomplish this by providing an inert gas circuit having low and higher temperature evaporators which are formed of piping and disposed at substantially the same level in the interior of a refrigerator, the low temperature evaporator providing a freezing section having a plate-like supporting surface and piping associated therewith, and the higher temperature evaporator providing an air cooling section including piping having a relatively extensive heat transfer surface. In a preferred embodiment the freezer and air cooling sections are disposed alongside one another and together occupy a major portion of the space across the cabinet interior at the front access opening thereof.

The novel features which I believe to be characteristic of my invention are set forth with particularity in the claims. The invention, both as to organization and method, together with the above and other objects and advantages thereof, will be better understood by reference to the following description taken in connection with the accompanying drawings forming a part of this specification, and of which:

Fig. 1 is a fragmentary front view of a refrigerator embodying the invention;

Fig. 2 is a horizontal sectional view of the refrigerator shown in Fig. 1 to illustrate details more clearly;

Fig. 3 illustrates more or less diagrammatically the type of refrigeration system with which the parts shown in Figs. 1 and 2 are associated; and

Figs. 4 and 5 are views similar to Fig. 2 illustrating other embodiments of the invention.

Referring to Figs. 1 and 2, a household refrigerator 10 is provided with a low temperature freezing section 11 which is disposed in a higher temperature food storage space 12. The freezing section 11 and storage space 12 are arranged to be cooled by a plurality of evaporators or cooling elements 14, 15 and 16 which are operable at different average or mean temperatures. The evaporators 14, 15 and 16 form part of an absorption refrigeration system of the inert gas type and are usually inserted into the storage space 12 at the rear of the refrigerator in any suitable manner, such as, for example, through an opening in the rear insulated wall which is adapted to be closed by an insulated closure member 17. A refrigeration system of this type is more or less diagrammatically shown in Fig. 3 in which the evaporators 14, 15 and 16 are illustrated apart from a household refrigerator.

The system illustrated is of a uniform pressure type

2

employing an inert gas or pressure equalizing agent. In Fig. 3 a refrigerant fluid, such as liquid ammonia, for example, is introduced through a conduit 18, into the evaporators 16, 15 and 14. The refrigerant fluid in the evaporators or cooling elements evaporates and diffuses into an inert gas, such as hydrogen, for example, to produce a refrigerating effect and abstract heat from the surroundings. The rich gas mixture of refrigerant vapor and inert gas formed in the evaporators flows from the evaporator 16 through a conduit 19, one passage of a gas heat exchanger 20, conduit 21 and absorber vessel 22 into the lower end of an absorber coil 23. In absorber coil 23 the rich gas mixture flows counter-current to downwardly flowing absorption liquid which enters through a conduit 24. The absorption liquid absorbs refrigerant vapor from inert gas, and inert gas weak in refrigerant flows from absorber coil 23 in a path of flow including a conduit 25, another passage of gas heat exchanger 20 and a conduit 26 which is connected to one end of the evaporator or cooling element 14.

The circulation of gas in the gas circuit just described is due to the difference in specific weight of the columns of gas rich and weak, respectively, in refrigerant vapor. Since the column of gas rich in refrigerant vapor and flowing from the upper end of evaporator 16 to the absorber coil 23 is heavier than the column of gas weak in refrigerant and flowing from such coil to the evaporators 14, 15 and 16, a force is produced or developed within the system for causing circulation of inert gas in the manner described.

From the vessel 22 enriched absorption liquid flows through a conduit 27 and an inner passage 28 of a liquid heat exchanger 29 into the lower end of a vapor lift pump 30 of a generator unit 31. The generator unit 31 comprises a heating tube 32 having the vapor lift pump 30 and a boiler pipe 33 in thermal exchange relation therewith, as by welding, for example. By heating generator unit 31, as by an electrical heating element within the lower part of heating tube 32 or by a fluid fuel burner, for example, liquid from the inner passage 28 of the liquid heat exchanger is raised by vapor lift action through pump 30 into the upper part of the boiler pipe 33. The liberated refrigerant vapor entering boiler pipe 33 through the pump 30, and also vapor expelled from solution in the boiler pipe, flows upwardly into an air cooled condenser 34 provided with a plurality of cooling fins 35.

Refrigerant vapor is liquefied in the condenser 34 and returned to the evaporators 14, 15 and 16 through the conduit 18 to complete the refrigerating cycle. Gravity flow of liquid refrigerant is effected through the evaporators, the evaporator 14 receiving liquid refrigerant from the upper evaporators 15 and 16. The outlet end of condenser 34 is connected by a conduit 36 to the gas circuit, as to the gas heat exchanger 20, for example, so that any non-condensable gas that may pass into the condenser will flow to the gas circuit and not be trapped in the condenser. The weakened absorption liquid, from which refrigerant vapor has been expelled, is conducted from boiler pipe 33 through a conduit 37, the outer passage 38 of the liquid heat exchanger 29 and conduit 24 into the upper part of absorber coil 23.

It will be understood that the evaporators 14, 15 and 16 in Fig. 3 are diagrammatically shown in their relation to other parts of the system, and that in Figs. 1 and 2 a practical form of the evaporator structure in accord with the invention is illustrated in which the evaporator 14 comprises a horizontally disposed coil located essentially in a single horizontal plane, and evaporator 15 also comprises a horizontally disposed coil located essentially in a single horizontal plane which is slightly above the horizontal plane of the evaporator 14 but essentially at

the same level in the interior of the refrigerator cabinet. The evaporator 16 comprises horizontally disposed piping positioned substantially at or slightly above the horizontal plane of evaporator 15. The evaporators 14, 15 and 16 are connected in series relation, and, while all of the conduit connections associated with the coils and piping may not be immediately evident in Figs. 1 and 2, it is to be understood that such connections are generally like those diagrammatically shown in Fig. 3.

Accordingly, flow of fluids takes place in Figs. 1 and 2 in the manner shown in Fig. 3, whereby inert gas weak in refrigerant flows from the absorber 23 through the conduit 25 to one passage of the gas heat exchanger 20 which is embedded in the insulated closure member 17 in the rear wall 39 of the cabinet. From the opposite end of such gas heat exchanger passage weak inert gas flows through conduit 26 to one end of the horizontal evaporator coil 14. As best shown in Fig. 1, inert gas emerging from evaporator coil 14 passes through an upwardly inclined connection 40 into the horizontal evaporator coil 15 and thence through the evaporator piping 16 which is connected by conduit 19 to one end of the other passage of the gas heat exchanger 20, the opposite end of which is connected by the conduit 21 to the lower end of the absorber coil in the manner shown in Fig. 3.

Liquid refrigerant formed in condenser 34 flows therefrom through conduit 18 which is connected to the end region of evaporator piping 16 at 41, as best seen in Fig. 2. Hence, in Fig. 2 liquid refrigerant initially passes from left to right in evaporator piping 16. The refrigerant then passes through evaporator coil 15 and finally flows through evaporator coil 14. With this arrangement liquid refrigerant flows in the presence of and in counterflow to inert gas in the evaporator piping 16 and both of the horizontal evaporator coils 14 and 15. In order to obtain good distribution of liquid refrigerant in the evaporator structure and promote evaporation and diffusion of refrigerant fluid into the inert gas, the piping and coils may be provided with suitable inserts, such as fine wire coils or screens, for example.

Since the inert gas flows successively through the evaporators 14, 15 and 16, the gas in the horizontal evaporator coil 14 contains a lesser amount of refrigerant vapor than the gas in the evaporator coil 15 and evaporator piping 16. The partial vapor pressure of the refrigerant is a gradient, so that the temperature of liquid refrigerant in the evaporator coils and piping also is a gradient, the evaporating temperature of liquid being lowest in the horizontal evaporator coil 14 which constitutes the freezing portion of the evaporator structure.

The refrigerating effect produced by the horizontal evaporator coil 14, which is adapted to be operated at temperatures below freezing, is primarily adapted to effect cooling of the freezing section 11. As shown in Fig. 1, the freezing section 11 comprises a shell 42 formed with a front access opening adapted to be closed by a cover plate or closure member (not shown) hinged to the shell in any suitable manner. A shelf or plate-like member 43 is provided within shell 42 to the underside of which is heat conductively connected the horizontal evaporator coil 14. A body of suitable insulation 44 is retained at the underside of shelf 43, so that evaporator coil 14 will efficiently transmit cooling effect to matter placed on the shelf, such as trays 45 containing water to be frozen, for example, and also prevent air in the storage space 12 from coming in direct contact with evaporator coil 14. The top 46 of the freezing section 11 is closely adjacent to the ceiling or roof of the storage space 12.

In the preferred embodiment illustrated, the horizontal evaporator coil 15 is located alongside the freezing section 11. In order to provide a relatively extensive heat transfer surface, a number of vertically extending heat transfer members or fins 47 are fixed to the horizontally extending arms of the coil 15. The refrigerating effect produced by the horizontal evaporator coil 15, which is

adapted to be operated at a higher temperature than that of evaporator coil 14 and desirably above freezing, is primarily utilized to cool air in the storage space 12, the relatively extensive heat transfer surface provided by the fins 47 promoting such air cooling. The inert gas leaving the horizontal evaporator coil 15 is relatively rich in refrigerant vapor. However, such enriched inert gas often may be employed to effect additional cooling and, as shown in Fig. 2, the rich inert gas passes from evaporator coil 15 into auxiliary evaporator piping 16 in which liquid refrigerant evaporates and diffuses into the rich inert gas.

It has already been pointed out that liquid refrigerant flows successively through evaporators 16, 15 and 14, respectively. Since the partial pressure of refrigerant vapor in the gas mixture in the evaporator piping 16 is less than the vapor pressure of the warm liquid refrigerant entering piping 16 through conduit 18, liquid refrigerant evaporates and diffuses into the gas mixture with consequent absorption of heat from liquid refrigerant in the evaporator piping 16. Hence, the highest temperature evaporator piping 16 not only functions to abstract heat from air in storage space 12 but also effectively serves as a precooler for liquid refrigerant. Such precooled liquid refrigerant subsequently flows to the horizontal evaporator coil 14 into the presence of inert gas which is weakest in refrigerant vapor, whereby effective low temperature cooling below the freezing temperature is effected in the freezing section 11. Since liquid refrigerant entering the evaporator coils 14 and 15 from the evaporator coil piping 16 flows by gravity through such piping and both coils, it is desirable to arrange successive straight portions and turns in the direction of liquid flow in such a manner that gravity flow of the liquid is promoted from the region 41 to a lower region at which conduit 26 is connected to one end of evaporator coil 14.

It will now be understood that evaporator structure of the horizontally extending type has been provided in Figs. 1 and 2 which takes up a minimum amount of usable space in the storage compartment or space 12. The freezing section 11 and higher temperature cooling elements 15 and 16 are essentially located at the same level adjacent the ceiling of the storage space 12, the freezing section 11 and higher temperature section 15 being disposed side by side and together extending entirely across the storage space 12 from one lateral side 48 to the opposite lateral side 48 of the refrigerator 10. The freezing section 11 may occupy from one-fourth to three-fourths of the total width of the storage space, the shelf 43 preferably being dimensioned so that a definite number of conventional trays 45 for producing ice cubes can be placed thereon alongside one another and occupy substantially the entire area of the supporting shelf. The freezing section 11 desirably should be of minimum overall height, the top wall thereof preferably being located at the immediate vicinity of and essentially in the same horizontal plane as the ceiling or top wall 49 of the storage space 12 of the refrigerator. Such minimum overall vertical height is obtained, of course, when the freezing section 11 is formed to accommodate a single horizontal row of trays 45. With such arrangement an adequate liquid head must be provided in the refrigerant supply line 18 leading downward from the condenser 34.

As diagrammatically shown in Fig. 2, the generator unit 31, absorber 23 and condenser 34 are disposed in a vertically extending apparatus compartment 50 at the rear of the refrigerator 10. Upward circulation of air is induced by natural draft in the compartment 50 which defines a vertically extending flue, and such upward movement of air effects cooling of the absorber 23 at one level and the condenser 34 located at a higher level. The straight portions of the condenser coil 34 are disposed essentially in the same horizontal plane or in a plane at a slight angle to the horizontal, such plane being at a level closely adjacent to the top exterior wall of the

refrigerator 10. With such disposition of the condenser 34 relative to the evaporator structure in storage space 12, a vertically extending path of flow for refrigerant is provided by conduit 18, whereby an adequate liquid head will be assured to promote gravity flow of liquid refrigerant through all of the evaporators or cooling elements 14, 15 and 16. However, the heat dissipating members or cooling fins 35 of the condenser 34 can extend vertically downward in the flue 50 a distance well beneath the horizontal plane of the evaporator coil 14.

The higher temperature evaporator coil 15 and heat transfer fins 47 fixed thereto desirably are distributed over a cross-sectional area of storage space 12 which is at least half of the cross-sectional area of the freezing section 11 and may be equal to the cross-sectional area of the latter. Further, the bundle of fins 47 is formed in such a manner that air circulating in space 12 can pass both in an upward and downward direction through the gaps in the bundle of fins. In certain instances it may be desirable to provide a small vertically extending gap between the top wall 49 and bundle of fins 47 which is at least as great as the distance between adjacent fins 47.

Since the bottoms of the freezer and air-cooling units are essentially at the same height, as best seen in Fig. 1, the region below these units provides an unobstructed compartment 12 which extends downwardly substantially at the same level from all regions of the bottoms of both the freezer unit 11 and air-cooling unit which includes the fins 47. The compartment 12 provided in this manner is of maximum cross-sectional area, and the same as that of the storage space defined by the inner liner of the cabinet, at successively lower levels through a vertical distance extending downwardly from the bottoms of both of the freezer and air-cooling units to the bottom of the storage space. Hence, the compartment 12 forms the only zone having such maximum cross-sectional area throughout substantially its entire height which is at a higher temperature than that prevailing in the freezer unit 11.

As previously explained, the evaporator piping 16 may be employed as an auxiliary high temperature cooling element in which evaporation of liquid refrigerant takes place in the presence of rich inert gas. As seen in Fig. 2, such auxiliary evaporator may be formed of a single length of piping which is provided with heat transfer fins 51 and disposed closely adjacent to the rear wall 39 at the rear of the evaporator coils 14 and 15.

In certain instances it may be preferable only to circulate relatively cool rich inert gas through the piping 16 and to initially supply liquid refrigerant to the evaporator coil 15, thus shifting the connection of conduit 18 from the region 41 to the region indicated at 52 in Fig. 2. Such a modification is illustrated in Fig. 4 in which parts similar to those shown in Figs. 1 and 2 and described above are referred to by the same reference numerals. In Fig. 4 the evaporator coil 14a having a single U-shaped loop is associated with a freezing section 11a capable of accommodating a single tray 45 for producing ice cubes. The higher temperature evaporator coil 15a comprises a single U-shaped loop having heat transfer fins 47a fixed thereto. However, it will be evident that the evaporator coils 14a and 15a may each comprise several U-shaped loops and connecting bends to provide an evaporator structure which extends up to three-fourths of the total width of the storage space 12. This arrangement provides a space at one side of the evaporator structure which extends downwardly from the top wall 49 of the storage space 12 to the position of the highest located shelf (not shown), so that tall items like bottles, for example, can be conveniently stored in the refrigerator.

In the embodiment of Fig. 4, the gas heat exchanger is provided by arranging the conduit 25a, through which weak inert gas flows from absorber 23 to evaporator coil 14a, in heat conductive relation with conduit 19a through which rich inert gas flows from evaporator coil 15a to

the absorber 23. Also, it will be seen that the refrigerant supply line 18a conducts refrigerant from condenser 34 to evaporator coil 15a at the region 32a.

Fig. 5 illustrates a further modification in which the low temperature evaporator coil 14b is associated with a freezing section 11b in the same manner as in Fig. 4. However, in Fig. 5 only a part of the higher temperature evaporator coil 15b is positioned alongside of the freezing section 11b while another part thereof occupies the space between the rear of the freezing section and the rear wall 39 of the refrigerator. This arrangement is particularly advantageous in household refrigerators of small size, because the ice cube trays in small size refrigerators generally are of such length that the freezing section terminates at a region removed from the rear wall 39 of the refrigerator. By locating part of the higher temperature evaporator coil 15b at the rear of the freezing section 11b, space which otherwise would not be used is effectively employed to effect space cooling. In each of the embodiments illustrated and described, it will be seen that the freezing section and higher temperature air cooling section are located substantially at the same level in the cabinet interior and together occupy a major portion of the space extending from one lateral side wall to the opposite lateral side wall of the cabinet interior.

Modifications of the embodiments of my invention which I have described will occur to those skilled in the art. Therefore, I intend in the claims to cover all those modifications which do not depart from the spirit and scope of the invention.

What is claimed is:

1. A refrigerator including a cabinet having thermally insulated top, bottom, rear and lateral side walls defining a single thermally insulated storage space and an absorption refrigeration system associated therewith having a circuit for inert gas including piping forming low and higher temperature evaporator sections in which refrigerant fluid evaporates in the presence of inert gas, conduit means in said circuit including said piping for effecting circulation of inert gas solely by the difference in specific weight of columns of gas rich and weak, respectively, in refrigerant vapor, a freezer unit in the storage space comprising wall means to provide a compartment substantially segregated from the rest of the storage space to restrict circulation of air therebetween, the piping of said low temperature evaporator section being in thermal exchange relation with said wall means which provides a supporting surface for matter to be refrigerated, an air cooling unit in the storage space comprising means providing a relatively extensive heat transfer surface and the piping forming said higher temperature evaporator section which is in thermal exchange relation therewith, said freezer and air cooling units, including all of said piping in the storage space forming a part of said units, being disposed in side by side relation between the lateral side walls of the cabinet, said freezer unit including a top horizontal wall part formed by said wall means which is essentially in the same horizontal plane as the ceiling of the storage space, means including said piping for flowing refrigerant fluid in the storage space in the presence of inert gas in a vertically extending path of flow which is in a vertical range entirely between the top and bottom, respectively, of said air-cooling unit, the region below said freezer and air-cooling units providing an unobstructed compartment which extends downwardly substantially at the same level from all regions of the bottoms of both of said units, and said compartment always having a maximum cross-sectional area, which is the same as that of the storage space, at successively lower levels through a vertical distance extending downwardly from the bottoms of both of said units to the bottom of the storage space, said compartment forming the only zone having such cross-sectional area throughout substantially its entire height which is at a higher temperature than that prevailing in said freezer unit.

2. A refrigerator including a cabinet having thermally insulated top, bottom, rear and lateral side walls defining a single thermally insulated storage space and an absorption refrigeration system associated therewith having a circuit for inert gas including piping forming low and higher temperature evaporator sections in which refrigerant fluid evaporates in the presence of the inert gas, conduit means in said circuit including said piping for effecting circulation of the inert gas solely by the difference in specific weight of columns of gas rich and weak, respectively, in refrigerant vapor, a freezer unit in the storage space comprising wall means to provide a compartment substantially segregated from the rest of the storage space to restrict circulation of air therebetween, the piping of said low temperature evaporator section being in thermal exchange relation with said wall means which provides a supporting surface for matter to be refrigerated, an air-cooling unit in the storage space comprising means providing a relatively extensive heat transfer surface and the piping forming said higher temperature evaporator section which is in thermal exchange relation therewith, said freezer and air-cooling units, including all of said piping forming a part of said units, being disposed in side-by-side relation and occupying a major portion of the entire space between the lateral side walls of the cabinet, said freezer unit being spaced from the rear wall of the cabinet with the top parts of both of said units being located at the immediate vicinity of and closely adjacent to their ceiling of the storage space, said air-cooling unit including a first portion in side-by-side relation with said freezer unit between the lateral side walls and a second portion in the space between the rear of said freezer unit and the rear wall of the cabinet, means including said piping for flowing refrigerant fluid in said storage space in the presence of the inert gas in a vertically extending path of flow which is in a vertical range entirely between the top and bottom, respectively, of said air-cooling unit, the region below said freezer and air-cooling units providing an unobstructed food storage compartment which extends downwardly at substantially the same level from all regions of the bottoms of both of said units, said food storage compartment constituting the only part of said single storage space available for storing food in a zone which is at a higher temperature than that prevailing in said freezer unit.

3. A refrigerator including a cabinet having thermally insulated top, bottom, rear and lateral side walls defining a single thermally insulated storage space and an absorption refrigeration system associated therewith having a circuit for inert gas including piping in said storage space forming low and higher temperature evaporator sections in which refrigerant fluid evaporates in the presence of

the gas, conduit means in said circuit including said piping for effecting circulation of inert gas solely by the difference in specific weight of columns of gas rich and weak, respectively, in refrigerant vapor, a freezer unit 5 in the storage space comprising wall means including a horizontal plate to provide a compartment substantially segregated from the remainder of the storage space to restrict circulation of air therebetween, substantially all of the piping of said low temperature evaporator section 10 being disposed essentially in a single horizontal plane, the piping of said low temperature evaporator section being in thermal exchange relation with said plate which provides a supporting surface for matter to be refrigerated, an air cooling unit in the storage space comprising 15 means providing a relatively extensive heat transfer surface and the piping forming said higher temperature evaporator section which is in heat exchange relation therewith, and said freezer and air cooling units, including all of the piping in the storage space forming a part 20 of said units, being disposed in side by side relation between the lateral side walls of the cabinet, said freezer unit including a top horizontal wall formed by said wall means which is essentially in the same horizontal plane as the ceiling of the storage space, means including said 25 piping for flowing refrigerant fluid in the storage space in the presence of inert gas in a vertically extending path of flow which is in a vertical range entirely between the top and bottom, respectively, of said air-cooling unit, the region below said freezer and air-cooling units providing 30 an unobstructed compartment which extends downwardly substantially at the same level from all regions of the bottoms of both of said units, and said compartment always having a maximum cross-sectional area, which is the same as that of the storage space, at successively 35 lower levels through a vertical distance extending downwardly from the bottoms of both of said units to the bottom of the storage space, said compartment forming the only zone having such cross-sectional area throughout substantially its entire height which is at a higher temperature than that prevailing in said freezer unit.
